UNITED STATES PATENT OFFICE

CURTIS L. HOWSE, OF DETROIT, MICHIGAN, ASSIGNOR TO DIAMOND POWER SPECIALTY CORPORATION, OF DETROIT, MICHIGAN, A CORPORATION OF MICHIGAN.

BOILER CLEANER

Application filed December 8, 1924. Serial No. 754,676.

The invention relates to boiler cleaners and has among its objects to provide a boiler cleaner for discharging jets of cleaning fluid adjacent parts of the boiler to be cleaned. A further object of the invention is to provide a boiler cleaner especially useful in connection with locomotive boilers although not necessarily limited thereto.

Referring to the drawings:—

Figure 1 represents a diagrammatic plan view partly in section of the rear of a locomotive showing a pair of blowers located in the side wall water legs of the boiler;

Figure 2 is a fragmentary elevation view of the same;

Figure 3 is a plan view in section of one of the blowers shown in Figure 1, the blower being in its projected position;

Figure 4 is an end view of the blower shown in Figure 3;

Figure 5 is a sectional view along the line 5—5 of Figure 3;

Figure 6 is a sectional view along the line 6—6 of Figure 3;

Figure 7 is a view of the parts shown in Figure 3, the blower being in its retracted position;

Figure 8 is a sectional view showing a modified construction of my blower;

Figure 9 is an end view of the same, and

Figure 10 is a sectional view along the line 10—10 of Figure 8.

Referring to the drawings 10 indicates a locomotive having a cab 11, fire chamber 12, boiler tubes 13, boiler tube sheet 14 and side wall water legs 15, all of which parts may be of the usual construction. Mounted preferably in each water leg is a blower A. Referring to Figure 3, each blower A comprises a

stationary housing or casing 16 having secured thereto a forwardly projecting tubular part 17 located within a sleeve 18 forming a housing for the blower A within the water leg. Slidably mounted within the part 17

45 is a sleeve 19 forming an outer wall of a plu-

rality of longitudinally extending passages 20, the side walls of which are formed by the walls 21 extending radially from the central rod 22 to the sleeve 19. The inner end of sleeve 19 is closed by a head 19' which forms a piston within the tubular part 17 for a purpose hereinafter to be more fully described. Secured to the outer end of the sleeve 19 and rotatably carried therewith is a blower head 23 provided with a plurality of discharge nozzles 24 communicating respectively with the passages 20. The nozzles 24 are directed at different inclinations whereby as the sleeve 19 is oscillated or rotated jets of cleaning fluid such as steam, 55 air, etc., will be directed to successively trace spaced parallel vertical lines across the tube sheet, each of the blowers A, where two blowers are employed, cleaning substantially half of the tube sheet as will be hereafter explained. 60

In order to cause the jets of cleaning fluid from nozzles 24, to discharge only when each nozzle is directed toward the tube sheet, as the blower head is rotated or oscillated, I provide a plurality of ports 25 communicating respectively with the passages 20 and adapted to successively register with stationary port 26 whereby cleaning fluid, such as steam, may be supplied by a steam supply pipe 27 and chamber 28 successively to the nozzles 24. The rod 22 has a rearwardly extending part 29 upon which is mounted a member 30 having openings 31 for slidably receiving pins 32 which are rigidly carried by the stationary housing 16. Secured to the part 29 as by a pin 33, is a collar 34 which may have a pin 35 projecting therefrom adapted to contact with a pin 36 carried by an annular member 36', the latter being carried by a 70 plate 30' secured to the member 30 as at 30°. A thrust bearing 37 is adapted to relieve the thrust caused by the projection of the blower head, as shown in Figure 3, and permit ready rotation or oscillation of the blower nozzles 75 80 85 90

in this position. As illustrated, in Figures 3 and 7, the plate 30 has a recess 30³ for receiving the annular member 36' and thrust bearing 37 and the recess 30³ has a lateral extension 30⁴ for receiving one end of the pin 36. For imparting oscillation or rotation to the blower head 23 and sleeve 19, I provide a worm 38 keyed to an operating shaft 39 which extends to a point convenient for operation as in the cab of the locomotive where, as shown in Figures 1 and 2, a hand wheel 40 serves to produce oscillation or rotation of the shaft 39. The worm 38 meshes with a worm wheel 41, one end of which is supported, as at 42. Fitted to the worm wheel 41 is an extension 44, rotatably mounted in stationary sleeve 43. Said extension 44 is keyed at 45 to shaft 29, whereby rotary movement of the worm wheel 41 is imparted to the shaft 29. Springs 46 serve to normally retain the parts in retracted position, as shown in Figure 7, the blower head 23 being housed within the sleeve 18 protected from the heat of the fire chamber. Admission of steam to the supply pipes 27 may be regulated by suitable valves 47 preferably arranged for operation in the cab of the locomotive.

In operation, with the parts of the blower in retracted position as shown in Figure 7, steam is admitted by valve 47 to one (or both) of the blowers, the steam passing through supply pipe 27, entering chamber 28 and thence around by pass ports 50 to in back of piston 19' to project the blower forwardly into the position shown in Figure 3. Steam will then pass through port 26 and such of ports 25 as may be registering therewith, the steam then passing longitudinally of the passages 20 communicating with the ports 25 to discharge the steam through the nozzles 24. The pressure of the steam acting against piston 19' and the blower head 23 will retain the blower in projected position as long as the steam is being supplied to the blower.

The operator in the cab 11 then rotates or oscillates the handwheel 40, the motion being transferred through shaft 39, worm 38, gear wheel 41, part 29 to the rod 22. Thus the sleeve 19 and blower head 23 are caused to oscillate or rotate successively registering ports 25 with the stationary port 26 whereby successive nozzles 24 direct jets of steam vertically across the tube sheet, the blowing arc of each nozzle being determined, as before, by the length of the port openings 26' and 25'. After the blowing operation, the steam supply to the blower A' is shut off, the spring 46' then operating to return the parts to their retracted position. Steam may then be supplied to the other blower, it being understood that two of such blowers are preferably provided as shown in Figure 1.

When pins 35 and 36 are used, the latter pin acts as a stop for the former pin at each substantially complete 360° rotation of the blower in opposite directions, the handwheel 40 in this instance being oscillated within the limits defined by the pin 36.

Should it be desired to continuously rotate the blower in a single direction, the pin 36 may be removed by removing plate 30', handwheel 40 in this instance being rotated continuously in the same direction.

After operation of one of the blowers A, the valve 47 controlling passage of steam thereto is operated to shut off the steam supply whereupon the springs 46 will act to retract the blower. The other blower A may then be operated in a like manner.

Referring to Figures 8, 9 and 10, I have shown a modification of my blower. In these figures the blower A' comprises a fixed housing or casing 16' within which rod 22' is rotatably and reciprocably mounted. To the forward end of rod 22' is fixed the blower head 23' the latter comprising a plurality of ports 24' varying in direction as described in connection with the blower shown in Figure 3. The ports 24' have rearwardly extending passages 20' terminating in ports 25'. Reciprocably mounted with blower head 23' and rod 22' but splined against rotation is a member 47' fixed to sleeve 48' which has a bearing in the housing 16'. Steam is supplied at 27' to the passage 28' and passes thence to supply port 26'. To the rear of rod 22' is fixed a plunger 49 normally forced rearwardly under the influences of spring 46' to retract the rod 22', blower head 23', member 47' and sleeve 48'. The rod 22' and blower head 23' are oscillated or rotated as before through the action of the operating shaft 39', worm 38' and worm wheel 41'.

In operation, when steam is admitted to the chamber 28' through the supply pipe 27', the blower is automatically projected to the position shown in Figure 8. As the shaft 39' is oscillated or rotated from the cab of the locomotive the movement is transferred through the gearing 38', 40' and rod 22' to the blower head 23' causing the ports 25' thereof to successively register with supply port 26'. The successive nozzles 24' direct jets of steam vertically across the tube sheet, the blowing arc of each nozzle being determined, as before, by the length of the port openings 26' and 25'. After the blowing operation, the steam supply to the blower A' is shut off, the spring 46' then operating to return the parts to their retracted position. Steam may then be supplied to the other blower, it being understood that two of such blowers are preferably provided as shown in Figure 1.

What I claim as my invention is:

1. A boiler cleaner comprising a casing having a cleaning fluid inlet and a supply port, a projectable blower head journaled in said casing having a plurality of ports adapted to be successively placed in communication with said supply port upon relative movement of the blower head and casing, and

means for relatively moving the blower head and casing whereby said successive communication is effected.

2. A boiler cleaner comprising a casing having a cleaning fluid inlet and a supply port, a blower head journalled in said casing having a plurality of ports adapted to be successively placed in communication with said supply port upon relative movement of the blower head and casing, means for relatively moving the blower head and casing whereby said successive communication is effected and a plurality of variably directed nozzles, each of said nozzles communicating with one of said last-named ports.

3. A boiler cleaner comprising a casing having a cleaning fluid inlet and a supply port, a blower head journalled in said casing having a plurality of ports adapted to be successively placed in communication with said supply port upon relative movement of the blower head and casing, means for relatively moving the blower head and casing whereby said successive communication is effected, and a plurality of nozzles communicating with said last-named ports, said nozzles varying in their angularity with respect to the axis of said blower.

4. In combination with a locomotive having a cab, a boiler tube sheet and a side wall water leg, a blower normally housed within said water leg and movable to project out of the same, said blower comprising a casing having a cleaning fluid inlet and a supply port, a blower head having a plurality of discharge nozzles adapted when the blower is projected to discharge cleaning fluid toward said tube sheet, and cleaning fluid supply passages therefor, and means controlled from the cab of the locomotive for relatively moving the blower head and casing for effecting a successive supply of cleaning fluid from said supply port through said passages to said discharge nozzles.

5. In combination with a locomotive having a cab, a boiler tube sheet and a side wall water leg, a blower normally housed within said water leg and movable to project out of the same, said blower comprising a casing having a cleaning fluid inlet and a supply port, a blower head having a plurality of discharge nozzles adapted to discharge cleaning fluid toward said tube sheet when the blower is projected, and cleaning fluid supply passages therefor, and means controlled from the cab of the locomotive for relatively moving the blower head and casing for effecting a successive supply of cleaning fluid from said supply port through said passages to said discharge nozzles, said nozzles being directed toward said tube sheet and varying in angularity with respect to each other.

6. In combination with a locomotive having a cab and a side wall water leg, a blower normally housed within said water leg and

movable to project out of the same, said blower comprising a casing having a cleaning fluid inlet and a supply port, a blower head having a plurality of discharge nozzles and cleaning fluid supply passages therefor, said nozzles being adapted to discharge cleaning fluid adjacent surfaces to be cleaned when the blower is projected and means for oscillating or rotating the blower head for causing successive registration of the said cleaning fluid supply passages with said supply port.

7. In combination with a locomotive having a cab, a boiler tube sheet and a side wall water leg, a blower normally housed within said water leg and movable to project out of the same, said blower comprising a casing having a cleaning fluid inlet and a supply port, a blower head having a plurality of discharge nozzles, and cleaning fluid supply passages therefor, said nozzles being adapted to discharge cleaning fluid toward said tube sheet when the blower is projected, means operated from the cab of the locomotive for oscillating or rotating the blower head for causing successive registration of the said cleaning fluid supply passages with said supply port, and means for automatically restricting the flow of cleaning fluid as the blower head is rotated or oscillated to such nozzles as are successively directed toward the tube sheet.

8. In combination with a locomotive having a cab, a boiler tube sheet and a side wall water leg, a blower normally housed within said water leg, said blower comprising a casing having a cleaning fluid inlet and a supply port, a blower head having a plurality of discharge nozzles and cleaning fluid supply passages therefor, means controlled from the cab of the locomotive for relatively moving the blower head and casing for successively supplying cleaning fluid from said supply port through said passages to said discharge nozzles, means for automatically projecting the blower from its said normal position to position the blower head within the fire box of the locomotive whenever cleaning fluid is supplied to the blower, and means for automatically retracting said blower whenever the cleaning fluid supply to said blower is cut off.

9. In combination with a locomotive having a cab, a boiler tube sheet and a side wall water leg, a blower reciprocably mounted within said water leg, said blower comprising a fixed casing having a cleaning fluid inlet, and a supply port, a blower head having a plurality of discharge nozzles adapted to be directed in turn towards said tube sheet and adapted to be successively placed in communication with said supply port upon relative movement of the blower head and casing, means operable from the cab for supplying cleaning fluid to said supply port, and means operable from the cab for rotating or oscil-

lating said blower head whereby said successive communication is effected.

10. In combination with a locomotive having a cab, a boiler tube sheet and a side wall water leg, a blower reciprocably mounted within said water leg, said blower comprising a fixed casing having a cleaning fluid inlet, and a supply port, a blower head having a plurality of discharge nozzles adapted to be directed in turn towards said tube sheet and adapted to be successively placed in communication with said supply port upon relative movement of the blower head and casing, means operable from the cab for supplying cleaning fluid to said supply port, means acted upon by said cleaning fluid for projecting said blower inwardly toward the firebox of the locomotive, and means operable from the cab for rotating or oscillating said blower head whereby said successive communication is effected.

11. In combination with a locomotive having a cab, a boiler tube sheet and a side wall water leg, a blower normally housed within said water leg, said blower comprising a casing having a cleaning fluid inlet and a supply port, a blower head having a plurality of discharge nozzles, and cleaning supply passages therefor, and means controlled from the cab of the locomotive for relatively moving the blower head and casing for successively supplying cleaning fluid from said supply port through said passages to said discharge nozzles, means controlled from the cab of the locomotive for controlling the supply of cleaning fluid to said supply port, means acted upon by said cleaning fluid for projecting said blower unit beyond said water leg, and means for automatically retracting the blower to its position within the water leg upon shutting off the supply of cleaning fluid.

12. A boiler cleaner comprising a casing having a cleaning fluid inlet, and a supply port, a blower head journalled in said casing having a plurality of ports adapted to be successively placed in communication with said supply port upon relative movement of the blower head and casing, and means for rotating or oscillating the blower head whereby said successive communication is effected, the said blower head ports being so arranged with respect to the supply port that the cleaning fluid is not supplied to those ports which are not directed toward the tube sheet.

13. A boiler cleaner comprising a fixed casing provided with a cleaning fluid inlet and a cleaning fluid supply passage communicating therewith, a blower member rotatably mounted in said casing and provided with a plurality of nozzles, a cleaning fluid supply passage for each of said nozzles formed in said blower member, each of said nozzle supply passages being provided with a port adapted to be placed in communication suc-

cessively with the cleaning fluid supply passage in said casing upon rotation of said blower member.

14. A boiler cleaner comprising a fixed casing provided with a cleaning fluid inlet and a cleaning fluid supply passage communicating therewith, a blower member rotatably mounted in said casing and provided with a plurality of nozzles, a cleaning fluid supply passage for each of said nozzles formed in said blower member, each of said nozzle passages being provided with a port adapted to be placed in communication with the cleaning fluid supply passage in said casing, and means to rotate said blower member, said nozzle supply passage ports being placed in communication with said cleaning fluid supply passage in said casing in sequence, upon rotation of said blower member.

15. The combination with a locomotive provided with a fire box, a boiler tube sheet forming one side of said fire box, a water leg forming another side of said fire box, of a blower having a portion housed within said water leg, said blower comprising a casing having a cleaning fluid inlet and a cleaning fluid supply passage connecting therewith, a blower member rotatably mounted in said casing and provided with a plurality of nozzles adapted to discharge jets of cleaning fluid toward said boiler tube sheet, a cleaning fluid supply passage for each of said nozzles, each of said passages having an inlet arranged to register with the passage in said casing, and means to rotate said blower member whereby said nozzle supply passages are connected in sequence to said cleaning fluid supply passage.

16. The combination with a locomotive provided with a fire box, a boiler tube sheet forming one side of said fire box, a water leg forming another side of said fire box, a blower having a portion housed within said water leg, said blower comprising a casing having a cleaning fluid inlet and a cleaning fluid supply passage connecting therewith, a blower member rotatably mounted in said casing and provided with a plurality of nozzles adapted to discharge jets of cleaning fluid toward said boiler tube sheet, a cleaning fluid supply passage for each of said nozzles, each passage being arranged for connection with the passage in said casing, and means to rotate said blower member, the connection of said nozzle supply passages to the fluid supply passage in said casing being dependent upon the rotation of said blower member.

17. A boiler cleaner comprising a fixed casing provided with a cleaning fluid inlet and a cleaning fluid supply passage communicating therewith, a blower member rotatably mounted in said casing and provided with a plurality of nozzles, a cleaning fluid supply passage for each of said nozzles formed in

said blower member, each of said nozzle passages being provided with a port adapted to be placed in communication with the cleaning fluid supply passage in said casing, and
5 means to rotate said blower member, the connection of said nozzle supply passages to said casing supply passage being controlled by the rotation of said blower member.

In testimony whereof I affix my signature.
